(57) **CLAIM**

The ornamental design for a hydraulic pump, as shown and described.

DESCRIPTION

This application contains at least one drawing executed in color. Copies of this patent or patent application publication with color drawing(s) will be provided by the Office upon request and payment of the necessary fee.

FIG. 1 is a top view of a design for a hydraulic pump according to the present disclosure.

FIG. 2 is a bottom view of the hydraulic pump of FIG. 1.

FIG. 3 is a front view of the hydraulic pump of FIG. 1.

FIG. 4 is a rear view of the hydraulic pump of FIG. 1.

FIG. 5 is a right side view of the hydraulic pump of FIG. 1.

FIG. 6 is a left side view of the hydraulic pump of FIG. 1; and,

FIG. 7 is a top-rear perspective view of the hydraulic pump of FIG. 1.

The shadowing shown in FIGS. 1-7 are for illustrative purposes only and form no part of the claimed design.
